Patented Apr. 3, 1855.

Fig. 2.

UNITED STATES PATENT OFFICE.

ANDREW MURTAUGH, OF NEW YORK, N. Y.

PULLEY ARRANGEMENT FOR DUMB-WAITERS.

Specification of Letters Patent No. 12,640, dated April 3, 1855.

To all whom it may concern:

Be it known that I, ANDREW MURTAUGH, of the city, county, and State of New York, have invented a new and useful Improvement in the Manner of Arranging and Operating Dumb-Waiters; and I do hereby declare that the following is a full, clear, and exact description of the same, reference being had to the accompanying drawings, forming part of this specification, in which—

Figure 1 is a front elevation of a dumb waiter arranged after my invention. Fig. 2 is a front elevation of the same arranged after the old plan.

Similar letters of reference indicate corresponding parts in both figures.

My improvement relates to that description of dumb waiter which is suspended by cords and weights and moved up and down suddenly by the hand of an attendant; and is designed to place the operation of hoisting and lowering the waiter under the perfect control of the attendant, and also render said operation very easy and convenient, and likewise prevent the mischief commonly experienced from sudden jarring, occasioned by too great force being suddenly applied to the waiter, by the hand, in its up and down movements.

The nature of my invention consists in suspending the waiter A, and the weight B, between two or more cords C, D, arranged in the manner shown in Fig. 1, to wit, the cord C, being attached fast to an arbor b, and carried up to and around a pulley or pulleys c, c, on the bottom of the waiter and then down to a large pulley d, and wound once around the same and then carried along horizontally until it arrives at the pulley e, under which it is passed and carried up to and around a pulley e', on the bottom of the weight and then down again and secured fast to the bottom of the case A, and the cord

D, being attached fast to the top of the box A', and carried down under a pulley or 45 pulleys f, f, and up again and around a pulley or pulleys g, and down again to and around a pulley g', on the top of the weight and up again and secured to the top of the case A'. 50

The suspending of the waiter and weight between two cords arranged as shown in the drawing enables me to dispense with the use of a crane in raising the waiter. And the arranging of the cords double over pulleys has 55 the advantage of giving a fixed end by which, as said end is secured to an arbor, they can conveniently be drawn taut, for by simply turning the arbor with a key the cord D will be wound upon it and the object just 60 mentioned effected. In order to prevent the cords again becoming slack I provide a ratchet i, and pawl j as shown, the ratchet being fast on the arbor.

To avoid friction and guide the waiter I 65 provide a series of grooved friction rollers a, a, a, a, and circular ways a', a', and to avoid the necessity of the attendant remaining by the waiter and holding it while the articles are being removed or put on to it, I 70 provide a ratchet h, and pawl h', so that the waiter may be prevented, if desirable, from descending when the power is taken off from the crank.

What I claim as my invention and desire 75 to secure by Letters Patent, is—

I claim the manner herein shown of arranging and suspending the waiter A and weight B, between two cords C, D, arranged double over pulleys, substantially as and for 80 the purpose set forth.

ANDREW MURTAUGH.
